DESIGN FOR A SUIT

Molly Levy, New York, N. Y.

Application June 2, 1945, Serial No. 119,852

Term of patent 3½ years

(Cl. D3—4)

To all whom it may concern:

Be it known that I, Molly Levy, a citizen of the United States of America, residing in New York, county of New York, and State of New York, have invented a new, original, and ornamental Design for a Suit, of which the following is a specification, reference being had to the accompanying drawing, forming part thereof.

Fig. 1 is a front view of a suit showing my new design.

Fig. 2 is a rear view thereof.

I claim:

The ornamental design for a suit, substantially as shown.

MOLLY LEVY.
